UNITED STATES PATENT OFFICE.

FRED C. DAMM, OF CHICAGO, ILLINOIS, ASSIGNOR TO INTERTYPE CORPORATION, OF NEW YORK, N. Y., A CORPORATION OF NEW YORK.

COMPOSING AND TYPE-CASTING MACHINE.

Application filed March 9, 1920. Serial No. 364,490.

My invention relates to composing and type-casting machines, and is particularly applicable to those generally known as linotypes.

5 In the standard linotype machine, circulating matrices are employed, which are stored in parallel magazine compartments from which they are released selectively by mechanism operated from a keyboard and 10 are collected in an assembler, together with suitable spacers dropped from a separate magazine. When sufficient matrices have been assembled to form a line, they are shifted by an indirect path into position between mold jaws to engage a mold slot which 15 is filled with metal from a reciprocating pot to form a slug. The matrices are then elevated to the top of the magazine and selectively distributed therein, while the slug 20 is shifted by rotation of the mold and transversely ejected therefrom into a suitable holder or galley.

With machines of this type, the length of line is determined by adjustment of the assembler and of the mold jaws to accommodate a line of matrices of the proper length, and by providing a mold slot of corresponding length. The slug ejector must also be of suitable size. Consequently, it is necessary, 25 when the length of line is to be changed, to make separate adjustments in four places. According to present practice, the operator shifts an assembler jaw, a mold jaw, the ejector, and changes the liners in the mold, the 30 last operation requiring the loosening of three screws, separating the mold walls, prying out one or both liners, inserting suitable liners, and tightening the screws to clamp the mold walls upon the new liners. Consequently, 35 the operations necessary in changing the length of line consume considerable time, every alteration resulting in a delay of several minutes, even with highly skilled operators.

40 A primary object of my invention is to eliminate this delay by providing a construction in which the parts requiring changes when the length of line is altered may be adjusted rapidly and accurately. 45 In the preferred form, I have accomplished this object by providing a single element, by manipulation of which the operator can simultaneously adjust all necessary parts of the machine to change the length of line.

It is well known that the standard line-

type mechanism is extremely complicated, and that great skill and constant attention are necessary to maintain the machines in condition for efficient operation. This condition is due partly to the large number of small parts accumulated by many years of improvement in details, and partly to the complicated system of handling the matrices and slug owing to failure to solve the mechanical problems connected with the elimination of such system and the substitution of direct transportation of the matrices and slug from one point to another. A further object of my invention is to improve the operation of the present machine by greatly simplifying the mechanism employed for handling the matrices and slug, partly through improvements in the construction of standard portions of the machine, and partly through a material change in the system of handling the matrices.

At present, the matrices, after being collected in the assembler, are shifted upwardly, then laterally, and are then lowered between the mold jaws into a position substantially in alignment with their original position in the assembler. While it is obviously much simpler and more desirable to shift the matrices in a direct line from the assembler to molding position, the machines heretofore devised embodying this feature have not been successful in use, and have not affected the universal employment of machines embodying the indirect shift above described. My construction, however, includes the solution of the problems connected with a direct shift, the details of which will be set forth in connection with the extended description of parts.

50 A feature of this phase of my invention is the devising of a slide block adapted to be located in the assembler in advance of the matrices and preferably circulating in the same way as an individual matrix, the block serving to prevent the forward matrices from 55 tilting during travel from the assembler to the mold. I have also provided a simple and positive construction corresponding to the mold jaws of the standard machine, in which the moving jaw is slidably mounted 60 for ready adjustment, and the fixed jaw is connected to the pot, insuring its positive location and accurate timing in moving into and out of engagement with the matrices.

65 I have further simplified and improved

the construction and facilitated the adjustment of the length of line by providing a practical, simple and strong mold of the non-rotating type. In connection therewith, 5 I have invented an improved form of slug adapted to be ejected endwise from the mold, and have provided ejecting means adapted to form an end wall of the mold slot and readily adjustable to vary the length 10 of the slot. My invention also includes the construction of a mold which is readily adjusted for different sizes of type, and which is so arranged that the slug may readily be trimmed during ejection therefrom. 15 One difficulty with the standard linotype is the amount of floor space required for each machine. While my simplified construction of the matrix-shifting mechanism and the mold materially reduce the size of 20 the machine, I also prefer to eliminate the ordinary sloping magazine located above the vertical channels which transfer the matrices from the magazine to the assembling belt. I prefer to employ a vertical 25 magazine preferably having curved compartments terminating directly above the belt, thus reducing greatly the depth of the machine, permitting it to be conveyed through standard doorways and increasing 30 the number of machines which can be set up in a given area.

While these are the general objects of my invention, other objects and advantages will be apparent from the following detailed description of the parts, taken in connection with the accompanying drawings, in which:

Fig. 1 is a front elevation,

Fig. 2 is a fragmentary plan view, parts being broken away,

Fig. 2^a is an enlarged detail view of the actuating mechanism,

Fig. 3 is a fragmentary front elevation on an enlarged scale with parts broken away,

Fig. 4 is a section on line 4—4 of Fig. 3,

Fig. 5 is a vertical section through a preferred form of matrix slide block,

Fig. 6 is a section on line 6—6 of Fig. 3, with the parts in molding position,

Fig. 7 is a similar view with the parts open in the position assumed immediately after molding,

Fig. 8 is a fragmentary section on line 8—8 of Fig. 3,

Fig. 9 is a section on line 9—9 of Fig. 3,

Fig. 10 is a fragmentary rear view of one end of the mold, and

Fig. 11 is a perspective view of the ejector.

60 While numerous features of my invention are applicable to a large variety of composing and type-casting machines and other machines having analogous mechanism, the specific embodiment which is disclosed herewith follows the general plan of the standard

linotype, and includes several of the mechanical units of said machine. For the sake of clearness and simplicity, such units have been generally shown in the drawings only diagrammatically, and will not be described in detail, as their construction and operation are thoroughly familiar to those skilled in the art.

The frame of my machine preferably includes a suitable horizontal bedplate 20 supported in any desired way, as by legs 21. At the right of the machine I mount on the bedplate 20 the matrix magazine and the mechanism for selectively releasing the matrices and conveying them to the assembler, all of which parts may be of the standard type. I have preferred, however, to employ a vertical magazine 22 comprised of a plurality of parallel compartments 23, preferably curved to diminish the speed of 85 the matrices dropped into the compartments, and terminating in a line above the constantly traveling conveyor belt 24, which preferably is inclined downwardly from right to left in the usual manner. With 90 the arrangement disclosed, it will be apparent that the compartments 23 at the left of the magazine 22 are relatively long, and those at the right are comparatively short. But it is well known that the number of 95 matrices required for different letters varies greatly in proportion to the frequency of use of each individual letter in the English language. Consequently, by placing the matrices containing the letters most frequently used in the compartments at the 100 left of the magazine, and arranging the matrices from left to right in accordance with the relative frequency of use of the letters carried therein, a sufficient quantity 105 of matrices may be stored in a vertical magazine, such as I have disclosed, even though the compartments at one end are relatively short.

I have disclosed the usual keyboard 25 with keys 26, each adapted to release a selected matrix and permit it to fall upon conveyor belt 24, the usual well-known mechanism for this purpose being preferably employed, one form of which is disclosed in the 115 patent to Albrecht et al, No. 913,447. It is understood, of course, that the matrix releasing mechanism engages compartments 23 adjacent their lower ends.

As shown best in Figs. 2 and 3, the matrices are carried by conveyor belt 24 over the usual vertical guide plates 27 and star-wheel 28 into the assembler, indicated generally as 29. The assembler, which is shown best in Figs. 3 and 4, includes a front wall 30 and a rear wall 31 mounted in parallel vertical position on the bedplate 20, each wall having longitudinal slide grooves 32 along its inner face adapted to receive the shoulders at the opposite edges of the stand- 120 125 130

ard linotype matrix, walls 30 and 31 constituting a slide along which successive matrices may travel in vertical position. Front wall 30 is provided with a longitudinal sight 5 aperture 33, through which the portion of the assembled matrices which carries guide letters is visible to the operator, who may thus detect any error in said letters and may accurately gauge the length of the line.

10 While the assembler may be constructed in a great variety of ways, I have disclosed walls 30 and 31 as being composed of entirely separate plates imbedded in the bedplate 20, said bedplate preferably being cut 15 away between said walls 30 and 31 for a purpose to be hereinafter indicated. I have also disclosed guide plates 27 as mounted on the assembler walls 30 and 31, and serving as bearings for the shaft of starwheel 28. As 20 is shown best in Fig. 1, I preferably employ the usual spacer magazine 34, from which the wedge-shaped spacers 35 may be dropped in the usual way, by manipulation of a key, through chute 36 in front of starwheel 28 25 and propelled thereby into the assembler 29. When the spacers 35 are of the usual construction, as in the form disclosed, they will depend through the space in bedplate 20 between the assembler walls.

30 I provide a stop or end for the assembler, against which the first matrix will be forced when the line is full, and which is so located that the operator may readily judge the number of matrices which may be added to 35 the line within the space allowed, facilitating the proper justification of the line. As my machine, in its preferred form, is intended to shift a complete line of matrices from the assembler toward the left in direct line along 40 the assembler slide channels 32, it is necessary that the stop forming the end of the assembler channel should be readily removable to permit the shifting of the completed line. For this purpose various constructions may 45 be employed, the one disclosed including a stop arm 37 pivotally mounted on rod 38 and extending through the sight opening 33 into the space between the assembler walls. Stop arm 37 preferably projects only a small part 50 of the distance between the front wall 30 and the rear wall 31, as such a construction facilitates the withdrawal of stop arm 37; and it is unnecessary to provide a stop across the entire width of the first matrix.

55 I preferably employ resilient means for normally maintaining stop arm 37 in active position in the assembler, one construction for this purpose including a coil spring 39 having one end attached to arm 37 and the 60 other to rod 38.

I provide means for rocking stop arm 37 about rod 38 to withdraw said arm from the assembler to permit the lateral shifting of the assembled line of matrices to the left into molding position. I prefer to retract stop

arm 37 by operation of a release key 40 pivotally mounted on the frame and suitably connected to stop arm 37, so that the depression of key 40 will rock said arm outwardly and free the assembler passage. Various connections for this purpose may, obviously, be provided, the specific form shown including an extension or tongue 41 on stop arm 37, as shown best in Fig. 4, said extension being engaged by a rod 42 extending between the upper extremities of arms 43, the lower ends of which are pivoted to the frame, as at 44, one of said arms 43 being connected by link 45 to release key 40 so that the depression of said key will operate through link 45 to swing arms 43 and rod 42 outwardly, said rod engaging extension 41 on stop arm 37 to swing the latter into inactive position. If desired, suitable spring means, such as spring 46, may be employed to normally maintain release key 40 in elevated position. While the specific stop releasing mechanism disclosed is the preferred form, it will be apparent that a great many variations therein may be made without departing from my invention.

Stop arm 37 is preferably mounted so that it may be shifted longitudinally of the assembler to vary the length of line. Various constructions for this purpose may be employed, it being apparent that the releasing mechanism is particularly adapted to accommodate the shiftable stop arm, and the assembler is arranged to cooperate therewith. In the construction disclosed, I prefer to 100 provide means for shifting rod 38 longitudinally of the assembler by means which will be described in connection with the mechanism of the molding station hereinafter set forth.

I provide means engaging the last matrix for conveying the assembled line of matrices along the slide grooves of the assembler and into the molding station. Various arrangements for this purpose may be provided. I prefer to employ a shifter block 47, shown best in Fig. 3, which slides longitudinally in ways beneath and in alignment with the assembler. A convenient arrangement of parts is to provide ways 48 in the lower part of the assembler walls 30 and 31; but any suitable construction may be employed. Block 47 carries the matrix engaging element which may consist of an arm 49 pivotally mounted in a central vertical slot in block 47, and provided at its forward end with a vertical thumb 50 adapted to bear against the last matrix when the line is shifted. I prefer to construct starwheel 28 in two laterally spaced parts, or to recess the flanges of said starwheel, so that thumb 50 may normally rest to the right of, and preferably below said wheel while the matrices are being assembled, and may advance between the laterally spaced parts 120 125 130

of the wheel into engagement with the last matrix without interfering with the constant rotation of said wheel.

Various means for bringing thumb 50 into active engagement with the last matrix and for retracting it out of position to interfere with the filling of the assembler, may be provided, one preferred form, illustrated best in Figs. 3 and 4, consisting of a transverse 5 guide rod 51, the opposite ends of which engage guide slots 51^a in the walls of ways 48, slot 51^a being preferably so designed that when shifter block 47 is in retracted position, thumb 50 will lie below starwheel 28 10 and to the rear of the assembler, the advance of the shifter block bringing thumb 50 into position to engage the last matrix at or about its vertical center, and maintaining said thumb in such position during the shifting 15 of the line of matrices.

As said line of matrices is shifted at the will of the operator when the line is completed, I provide manually controlled means 20 for moving slide block 47 to the left, simultaneously transferring the matrices from the assembler to the molding station. For this purpose, I employ a shift rod 52, shown best in Fig. 3, located beneath and in longitudinal alinement with the assembler and slideable 25 in brackets 53 and 54 carried by the frame. Shift rod 52 is connected with shift block 47, as by a vertical arm 55 located at the extreme right hand end of said shift rod and connected to the lower face of the block 47. To shift the rod 52 to the left, I 30 may employ a spring 56 coiled about said rod 52 bearing at one end against bracket 54 and at the other against a collar 57 on said rod 52. Rod 52 may carry an arm 58 on 35 which is mounted a roller 59 adapted to engage a cam 60 (Fig. 1), designed to return the rod 52 to the right against the action of spring 56.

I provide means for normally maintaining 40 shift rod 52 and shift block 47 in inoperative position at the extreme right of their travel paths, said means being releasable at the will of the operator to shift the assembled line of matrices. For this purpose, I may 45 employ a suitable catch or latch engaging shift rod 52 and holding it at the extreme right of its travel. Various forms of latch may be employed. I prefer to provide the release key 40 with a pivot 61 mounted at 50 its ends in bracket 54 and the keyboard frame respectively, said pivot 61 carrying a sleeve 62, upon one end of which is mounted key 40, the other end carrying a latch 63, adapted 55 to engage notch 64 in shifting rod 52 when said rod is at its limit of movement to the right.

It will be apparent that various other latch constructions may be employed, either 60 connected to or independent of release key 40; but I prefer to connect latch 63 to said

key, as such a construction insures the simultaneous withdrawal of stop arm 37, and the release of shift rod 52, a proper proportioning of the parts assuring the complete retraction of said arm 37 from the path of the matrices before latch 63 is out of engagement with notch 64, and preventing any possibility that the thrust of thumb 50 will be transmitted to stop arm 37.

While I have shown the slide grooves 32 in Fig. 4 as snugly fitting the lateral shoulders of the matrices, it will be apparent that this is purely illustrative, as it may be found desirable to support said matrices adjacent their lower ends only, to facilitate manual removal of individual matrices in case of error or in other ways; and under such circumstances, it will be evident that the first matrix may develop a tendency to tilt or fall, especially when shifted from the assembler to the molding station. To avoid the possibility of such an occurrence, I may employ a special matrix slide block 65, shown best in Fig. 5, consisting of two parts laterally slidable in relation to each other, as by providing screws 66 having shanks slideable in bearings in one part and threaded into the other, said blocks being expanded laterally, as by springs 67 located between and thrusting against both blocks. Slide blocks 65 are 85 preferably of substantial thickness, as shown in Fig. 3, and are provided with a sufficient range of lateral expansion, adjustable by suitable manipulation of screws 66, so that said blocks will bear against the sides of the 90 assembler 29 and will serve to maintain the matrices in accurate alinement during shifting thereof. Slide blocks 65 may be similar in contour to the matrices, and are adapted to circulate in the same manner, preferably being stored in the compartment 23 at the extreme left of the magazine.

As a slide block 65 is preferably used at the beginning of each line, I may employ means for automatically releasing a slide 110 block 65 after a line has been shifted and as soon as the assembler is ready to receive a new line. Various arrangements for this purpose may, obviously, be made. I prefer to employ a construction similar to that shown in Fig. 3, in which the matrix releasing mechanism connected to the compartment 23 containing slide block 65 is actuated by the usual keybar 68, upon which is mounted a cam shoulder 69. Shift block 47 carries a trip arm 70 on the lower side thereof, said arm having a bevelled lower face 71 co-operating with the shoulder 69, so that the return movement of block 47 will carry face 71 across said shoulder, depressing key 68 and releasing a slide block 65 as the shift 120 block 47 reaches the limit of its return motion. To prevent operative engagement of trip arm 70 with shoulder 69 during the active stroke of shift block 47, said trip arm 125

70 is preferably pivotally mounted on said block 47, and is provided with a stop lug 72 engaging said block 47 adapted to prevent the trip arm 70 from swinging to the left 5 out of operative position with engaging shoulder 69 during the return movement of shift block 47.

In the usual operation of linotype machines, the line of matrices, upon being 10 shifted from the assembler to the molding station, is held between the jaws while the wedge-shaped spacers are driven up to justify the line, the mold engages the intaglio faces of the matrices, and the pot 15 advances, filling the mold slot with metal forming a line of type, or slug. I have disclosed an embodiment of my invention which employs the same series of operations, though obviously a different method of procedure 20 may be employed in machines embodying my invention which are not designed to accomplish the same object, or which include additional or different steps.

In general, I employ a suitable matrix 25 holder such as an elevator provided with guide channels into which the line of matrices is shifted from the assembler against an adjustable end wall carried by the bedplate 20. The rear end of the line of matrices 30 is held in position during molding by a rear wall thrust into position behind said matrices by the advance of the pot holding the molten metal.

The elevator preferably includes a front 35 wall 73 and a rear wall 74 held in parallel relation, as by bolts 75 and spacing blocks 76, said walls during matrix shifting and molding being in alinement with assembler walls 30 and 31 respectively, and being provided 40 with slide grooves 77, which are maintained in alinement with grooves 32 during said operation. Wall 74 is relatively short vertically, and extends only far enough to engage the shoulders adjacent the upper end 45 of the matrices, exposing the side walls thereof which contain the intaglio letters.

I provide an adjustable end wall for abutment by the line of matrices. Said end wall is constituted by the face of the end 50 78 of a vertical plate 79 (Fig. 3) adapted to slide longitudinally between walls 73 and 74 of the elevator. Laterally projecting from the lower edge of plate 79 toward the front of the machine is baseplate 80 adapted to slide 55 on the bedplate 20 of the machine.

I provide means for adjusting the position of plate 79 to conform to variations in the length of line. One means for accomplishing this purpose is disclosed best in 60 Figs. 3 and 8, and includes a horizontal shaft 81 mounted in bearings in the bedplate 20 of the machine, and carrying a pinion 82 meshing with a rack 83 formed in or carried by the lower part of plate 79. 65 A handwheel 84 is keyed to the outer end of

shaft 81 and by means of a spring 85 bearing against the head 86 of said shaft and the end of a recess in wheel 84, is forced inwardly against bedplate 20. A dial 87 on handwheel 84 bears against a dial 88 mounted in fixed position on the bedplate 20 and provided with a suitable marginal scale. It will be apparent that the rotation of handwheel 84 through the engagement of pinion 82 and rack 83 will shift the end 70 wall 78 in either direction, depending upon the direction of rotation of the handwheel; and a suitable arrow on dial 87 cooperating with the scale on dial 88 will indicate accurately the extent to which end wall 78 is 75 shifted. It is most convenient to provide indications on dial 88 which will enable the operator to determine the number of ems which will be accommodated in the elevator when the dial and end wall are in a position indicated by the relation of the arrow on dial 87 in reference to said scale. If desired, suitable step by step engagement, such as the usual pin and socket arrangement, 80 may be provided between dials 87 and 88, 85 spring 85 permitting the release of such engagement for adjustment of the length of line and assuring accurate adjustment. It will, therefore, be apparent that I have provided means for readily and accurately adjusting the molding station to accommodate 90 a line of matrices of any predetermined length.

While I have invented and described an assembler which is adapted to be rapidly and accurately adjusted to any desired length of line independently of the remaining mechanisms, I prefer to provide means for adjusting said assembler concurrently with the adjustment of the molding station 100 when the length of line is altered. For this purpose, in the illustrated embodiment, I have mounted stop arm 37 of the assembler on a rod 38, as heretofore described; and in the preferred form, said rod is mounted on 105 base plate 80 forming a part of end wall 78 and moving therewith, the connection being shown best in Figs. 3, 6 and 7. It will be evident that the distance between the matrix engaging face of end wall 78 and stop arm 110 37 is fixed, and that the accurate adjustment of said end wall in the manner heretofore described, or in any other preferred way, will also operate to adjust accurately the 115 length of line in the assembler.

While various forms of guides may be employed to maintain end wall 78 in proper position, I have disclosed a thrust block 89 mounted on the bedplate 20 in position to contact with the elevator wall 73 and receive the force of the forward thrust during molding, this position being shown in Fig. 6. I also provide a guide block 90 to the left of thrust block 89, as shown in Fig. 8; and if desired, said blocks 89 and 90 may 120 125 130

be integral. Guide block 90 is provided with a suitable sliding engagement with end wall 78, as by an overhanging portion of the block engaging a guideway 91 in the upper 5 face of baseplate 80, this construction being particularly simple and effective, since the removal of guide block 90 permits wall 78 to be removed without other manipulation.

Broadly speaking, the mold consists of a 10 unit mounted on bedplate 20 and provided with a horizontal slot opening at the front of the mold in alignment with the intaglio portion of the matrices. An oscillating pot carrying molten metal is mounted in the rear 15 of the mold and has a spout adapted to be swung against the rear opening of the mold slot, ejecting the metal into the slot to form a slug after the matrices have been clamped in the molding station and justified.

20 It will be apparent that my invention as heretofore set forth can be employed with various types of mold and various relative arrangements of mold and pot. I prefer, however, to avoid a complicated mechanism 25 and the inconvenience of a rotary mold by employing a mold substantially fixed in position and mounted on the upper surface of bedplate 20. The mold, as is shown best 30 in Fig. 10, includes a top plate 92 and a bottom plate 93, between which the molding slot is formed. Plates 92 and 93 are connected in any desired manner, preferably being readily separable for a purpose herein-after described. In the specific embodiment 35 disclosed, I employ a pair of hand-screws 94 preferably engaging plates 92 and 93 at the left of the mold slot and in rearward exten-sions 95 of said plates.

40 While the mold may be mounted rigidly on bedplate 20, the usual linotype matrix is provided with a projecting shoulder below the intaglio letter thereon; and as the matrices are preferably shifted out of molding position by a vertical movement of the elevator, it is necessary, if standard matrices are 45 employed, to shift the mold and matrices away from each other prior to the elevation of the former. I prefer to provide this relative movement by shifting the mold rear-wardly as soon as the slug is cast, the move-50 ment necessary being very slight, as the matrix shoulders are of relatively limited size.

55 Various means for shifting the mold may be employed. I prefer to provide suitable guides on the bedplate 20, such as tracks 96 engaging corresponding grooves in the bottom mold plate 93, the tracks 96 being preferably tapered somewhat to prevent 60 play. To limit the motion of the mold, I may employ guide screws 97 (Figs. 1, 2 and 9) passing upwardly through the bed-plate 20 and threaded into the bottom mold plate 93, each screw 97 being provided with 65 an enlarged shank 98 fitting in a guide slot

99 which serves to regulate and limit the mold movement. While the mold may be shifted in various ways, I prefer to employ the thrust of the pot against the mold to shift it forward into engagement with the 70 matrices, the rearward movement of the pot being produced by springs 100 preferably connected at one end to the mold and at the other end to bedplate 20, as this arrangement releases the matrices as soon as the molding is completed and the pot starts to re-cede, permitting prompt distribution of said 75 matrices.

As above indicated, a principal object of 80 my invention is to provide an adjustable end for the mold slot to permit ready changes in the length of line. For this purpose, I may employ a blade 101 adapted to fit accurately 85 between the upper and lower mold plates, the end face 102 of the blade 101 forming the end wall of the mold slot. In the preferred 90 form disclosed, I also employ blade 101 to eject the slug endwise from the mold, and consequently prefer to describe blade 101 as 95 the ejector blade; but it will be apparent that when this feature of my invention is applied to constructions differing substantially in other parts from that disclosed, the arrangement of mold parts which includes 100 the adjustable ejector blade 101 may be 105 employed within the scope of my invention without using said blade as an ejector.

100 I have disclosed means for readily ad-justing the position of the ejector blade 101; and while the provision of a sliding blade in this position obviously facilitates the ad-justment of the length of line, which may be 105 accomplished in any desired way, I prefer to provide a connection between said blade and the means for adjusting the position of 110 end wall 78, so that the capacity of the mold-ing station will always correspond to the length of the mold slot. I may accomplish this object by providing a direct connection 115 between end wall 78 and ejector blade 101, the specific arrangement disclosed, which is shown best in Fig. 2, including a pin 103 mounted on blade 101 or the parts rigidly connected thereto, and engaging a suitable 120 recess 104 in end wall 78, the length of pin 103 being sufficient to maintain it in en-gagement with the recess 104 when the mold 125 is in its retracted or rearmost position. I provide a horizontally elongated recess 104, when the blade 101 is employed as an ejector, spring means hereinafter described being employed to retract the ejector and main-tain pin 103 in engagement with an end 130 wall of recess 104 during molding, this ar-rangement permitting the free reciprocation of the ejector blade 101, but assuring the proper registration of the end face 102 of 135 said blade and the matrix engaging face of the end wall 78 during molding. When a matrix slide block 65 is employed, face 102

will project to the right beyond end wall 78 a distance equal to the width of said slide block; but when no slide block is employed, said face 102 and end wall 78 will be approximately flush during molding.

While any desired contour may be given to the upper and lower walls of the mold slot, I have devised a form of slug which is adapted to be employed in the usual way, and 10 is possessed of sufficient rigidity to withstand the ordinary strains thereon, but which at the same time is economical of metal. At the same time, the slug is capable of end-wise ejection, the ordinary slug being unsuited for production in this manner because of its contour. To accomplish these 15 objects, I prefer to form a slug in the shape generally known as I-beam, illustrated by the cross-sectional contour of the ejector 20 blade 101 shown in Fig. 11, as this particular proportioning of the slug parts provides the maximum of resistance to pressure on the face of the type for the amount of metal employed, and also provides a type-carrying 25 face of full width and a rear face of similar extent; as well as lateral flanges forming the edges of the front and rear faces which facilitate the accurate positioning of the slugs one upon another in the galley. 30 Whatever type of slug is employed, the ejector blade 101 will be of similar contour, as it fits snugly between the upper and lower walls of the mold slot.

The reciprocation of the ejector blade, including the ejecting stroke and return stroke thereof, may be accomplished in various ways. In the preferred form disclosed, I have provided a guideway 105 in an extension 106 either integral with or mounted on 35 the lower mold plate 93, shown best in Figs. 2, 3 and 9. Ejector slide 107 is mounted to reciprocate in the guideway 105, and includes a driving rod 108 engaging ejector blade 101. Any preferred form of engagement may be provided, or the driving rod 40 108 and ejector blade 101 may be integral. To reciprocate the ejector slide 107, I may employ a rock arm 109 (Figs. 1, 2 and 9) adapted to be oscillated in any desired way, 45 as by engagement of a roller 110 on said arm 109 with a suitable cam on cam shaft 111. I preferably employ an edge cam, and maintain roller 110 in engagement therewith by 50 a suitable spring (not shown) connecting arm 109 and the frame of the machine. The upper end of rock arm 109 engages ejector 55 slide 107, and to minimize the friction between said rock arm and slide, I may provide a roller 112 rotatably mounted on said slide 107, against which rock arm 109 bears 60 when in operative position.

With this construction, the forward stroke of rock arm 109 will shift ejector carriage 107 and ejector blade 101 to the right, ejecting 65 the slug from the mold. To retract

the slide and ejector blade, I may employ a spring 113 (Figs. 3 and 9) connected at one end to the frame and at the other end to a portion of the slide 107 extending downwardly into the slot in bedplate 20 in which 70 arm 109 reciprocates. It will be apparent that this construction permits the ejector slide 107 to return, with its speed regulated by the cam action, until pin 103 engages the rear end of recess 104, at which time the ejector blade will be halted in proper register with end wall 78, the remaining motion of the rock arm 109 being without effect on the ejector mechanism. This arrangement provides a fixed motion for the rock arm 109 75 and an accurately timed operation of the ejector, while preserving the proper register of said blade and end wall, regardless of the length of line and without interfering with the adjustment of length of line at any time 80 except during the moment when the metal is actually being poured into the mold slot.

It is sometimes necessary or desirable to employ the same machine for producing slugs varying in thickness. It will be obvious that 85 the mold construction, as above described, is of such a simple nature that numerous arrangements for varying the slug thickness may be embodied therein. I have disclosed one construction for accomplishing this object. In the specific form illustrated, I employ upper and lower liners 114 (Fig. 10) 90 adapted to be mounted on the inner faces of the mold plates 92 and 93 in any desired way, as by providing a dovetail connection 115 95 which permits the liners 114 to be readily slid out of the mold laterally and replaced by others varying in thickness.

I also prefer to provide means for trimming the upper, lower, and rear faces of the 100 slug as it is ejected from the mold. For this purpose, I may employ trimming knives 116 which are preferably mounted on the ends of liners 114, so that the space between 105 blades 116 is always the same as that between 110 said liners; but if desired, blades 116 may obviously be mounted independently of the liners and separately adjusted. I also provide a blade 117, (Fig. 2) preferably mounted on an extension 118 of the lower mold 115 plate 93 and adjusted to trim the rear face of the slug during ejection.

It will be evident that when the thickness of the slug is changed, an ejector blade 101 120 of suitable size must be substituted. When the interchangeable liners 114 are used, I prefer to provide a readily detachable connection between drive rod 108 and ejector blade 101, the form disclosed including an extension 118 of the ejector blade, provided 125 with sockets 119 adapted to receive pins 120 (Fig. 2) on the upper face of the cut away end of rod 108, this construction assuring rigid connection between the ejector blade and said rod 108, and at the same time per- 130

mitting the ready assembly and replacement of ejector blade 101 when the top of the mold is removed to change liners 114.

When this construction is employed, I prefer to mount pin 103 upon drive rod 108. I also provide a guide channel 121 between the mold plates 92 and 93 to the left of the mold slot, the extension 118 and the underlying portion of rod 108 being preferably so proportioned that they fit snugly within said guide channel 121, which positively maintains the connection between the ejector blade 101 and said rod 108 during operation of the machine, and also provides a support for said blade, independent of the engagement of its ejecting end with the liners 114, thus assuring accurate engagement of the ejector with said liners and preventing tilting and jamming thereof.

It will be noted that, while I have provided a mold adjustable to various sizes of type, the construction employed is such that the mold may be readily and rapidly replaced in its entirety by another mold; and my invention includes a construction adapted to be employed in that way. It will also be apparent that, while I have described the entire mold construction from the right-hand end of the mold slot to the left-hand end of extension 106 as reciprocating slightly, my invention also includes constructions in which there is no mold reciprocation, or where only the slot-carrying portion of the mold reciprocates, as such variations in the construction disclosed are within the skill of a mechanic.

I prefer to employ the usual wedge type spacers 35 (Fig. 3) and provide means for forcing the spacers upwardly to justify the line in the usual way. Various constructions for this purpose may be employed, the form illustrated including a justifying slide 122 mounted in suitable ways 123 below the bedplate 20 and provided with an upper surface 124 adapted to engage simultaneously the lower ends of the spacers. When the shift rod 52 is located directly below the center line of the assembler and molding station, surface 124 is preferably carried by an offset portion 125 of the justifying slide 122, as shown best in Fig. 7. The slide 122 is elevated to justify the line at the proper time by any desired means, such as link 126 (Fig. 1) connecting the slide with a lever 127 having a roller 128 engaging a cam 129, said cam being suitably contoured to maintain the justifying slide 122 in inactive position against the upward pull of spring 130, attached to lever 127 and the frame of the machine, during the shifting of the matrices into the molding station and the positioning of the right-hand wall of said station in position to engage one end of the matrix line. Cam 129 then permits lever 127 to be moved upwardly by spring 130, so that justifying

slide 122 resiliently forces spaces 35 upwardly to justify the line. After the slug has been cast, slide 122 is again depressed by cam 129 into inactive position.

Any preferred construction may be employed for pouring the slug-forming metal into the mold slot, the ordinary rocking pot of the standard linotype being adapted for the purpose. In the specific construction disclosed, however, I have shown a pot 131 (Figs. 2 and 6) provided with the usual main reservoir 132 and the ejector reservoir 133 from which the molten metal is poured or ejected through spout 134 by the action of the usual plunger (not shown) in reservoir 133, the pot construction and plunger operation being standard and well-known in the art, and the details thereof being omitted in the drawings for the sake of clearness. Pot 131 is reciprocated into and out of engagement with the mold, being mounted on suitable guideways 135 on bedplate 20, which is cutaway between said guideways to accommodate the lower part of the pot. I have disclosed one construction for reciprocating the pot, which includes a toggle having an arm 136 pivoted to bedplate 20 at 137 at the rear of the pot, and toggle arm 138 pivoted at 139 (Figs. 2 and 6) to the pot. Said toggle arms are pivoted at 140 to operating link 141, which is reciprocated in any desired way, as by means of a spring 142 bearing against a collar 143 carried by said link 141 and against an abutment 144 on the frame of the machine, spring 142 tending to maintain pot 131 in engagement with the mold. Said link 141 is connected to the upper end of a lever 145 pivoted at its lower end on the frame of the machine, and carrying a roller 146 engaging cam 147 which is adapted to retract link 141 and withdraw the pot through the action of the toggle, after molding has taken place. Figures 6 and 7 show the pot, mold, and molding station in molding and inactive positions respectively.

While the mold may be shifted into and out of engagement with the line of matrices in the molding station in any desired way, the construction disclosed is such that the forward shift of the mold is produced by the advance of the pot, spout 134 contacting with the rear of the mold and forcing it into engagement with the matrices, thus insuring complete engagement of the spout, mold and matrices during pouring. After the slug is formed, the retreat of the pot 131 permits the mold to recede through the action of springs 100, until the front face of the mold slot is clear of the shoulders on the matrices, this shift also providing a slightly longer time for the metal to harden adjacent spout 134. When the retreat of the mold is halted, as by engagement of screw shanks 98 with the rear walls of slots

99, the continued withdrawal of the pot 131 breaks the connection between the rear wall of the slug and the mouth of spout 134, facilitating the ejection of the slug.

5 One of the principal problems connected with the employment of an assembler communicating directly with the molding station is the provision of an end wall for said molding station at the rear of the matrices, 10 adapted to hold them in the molding station against an adjustable wall thereof. This rear wall preferably is located in the path of travel of the matrices; and while my invention in its broad scope includes various arrangements 15 for locating the righthand wall of the molding station in place after the matrices are in the station, the construction which I prefer to employ includes an end wall which is shifted laterally into and out 20 of position in the molding station in synchronization with the shifting of said matrices.

One convenient method of accomplishing this operation is to shift said wall into and out of operative position by means of a connection 25 with pot 131, thus assuring perfect timing; and in the form disclosed, I have mounted said wall, which is in the form of a vertical plate 148, directly on the pot, preferably at one side of spout 134, the 30 mold being provided with a suitable recess 149 (Fig. 10) through which the end wall 148 may pass.

In the specific form disclosed, I also employ wall 148 as an end wall both of the 35 molding station and of the mold slot, said wall 148 being so located that it extends directly across the end of the mold slot when in operative position. However, my invention is not limited to this specific arrangement, as it is apparent that various forms 40 of shiftable wall for both the molding station and mold slot may be substituted within the scope of my invention and employing the advantages of the combination with 45 the remaining portions of the specific embodiment thereof which I have disclosed.

Any suitable arrangement for distributing the matrix after the slug has been cast 50 may be employed. Where the usual sloping magazine with vertical delivery channels adjacent thereto is employed, the ordinary method of distributing matrices from the molding station may be used. In the specific form disclosed, however, I employ, 55 as already set forth, a vertical magazine 22, and elevate the matrices directly from the molding station into alinement with the top of said magazine, the distributing mechanism being preferably similar to that employed 60 in standard machines of this type. In the preferred form disclosed, an elevator slide 150 is mounted in vertical guideways 151 carried by the frame of the machine, slide 150 being connected to the elevator walls 73 and 74, as by extensions 152 of said

slide, as best shown in Figs. 6 and 7. At the upper end of the elevator guideway, the usual distributing mechanism is mounted, including a channel 153 into which the matrices are shifted by a sliding distributor block 154, the matrices being distributed from the channel 153 to the magazine compartments 23 in the usual way. Block 154 is preferably forced normally toward the magazine by resilient means, and is retracted beyond the guides 151 during the elevation of a line of matrices from the molding station. Any desired mechanism may be employed to perform this operation, the form disclosed including a vertical rock 80 arm 155 mounted at its lower end on the frame of the machine, and connected at its upper end by means of link 156 to distributor block 154, which is normally forced to the right by spring 157 connected to rock arm 155 and the frame of the machine. Block 154 is retracted to engage the elevated line of matrices by means of the engagement of a roller 158 on said arm 155 with a suitable cam 159.

Any desired method of actuating the various parts of the machine may be employed. In the form disclosed, I have used substantially the arrangement of the standard linotype machines, though obviously many other methods of driving the parts may be substituted. With the arrangement disclosed, however, the method of driving the portions of the machine which are merely indicated generally will be apparent to those skilled in the art, as such portions may be driven in the same way that is used in standard machines, the details of the mechanism and driving connections being omitted for the sake of clearness.

In the form disclosed, I employ a main drive shaft 160 having a driving connection with cam shaft 111, as by pinion 161 meshing with gear 162, said pinion and gear being proportioned to permit a relatively rapid rotation of shaft 160 while maintaining the necessarily slow rotation of cam shaft 111. Upon said cam shaft 111 are mounted the cams hereinbefore described for shifting the pot, returning the matrix-shifting mechanism to normal position through shift rod 52, and operating the justifying and elevator slides and the distributor block. Attention is called to the fact that while obviously any desired type of actuation may be employed, I have provided a construction in which all of the moving parts are operated by rock arms oscillated through edge cams in one direction and returned by means of springs, this arrangement preventing breakage of parts if any portion of the machine should become jammed or clogged, and producing a simple, compact and strong machine.

The mechanism which, in the preferred

form, is controlled through cam shaft 111, may be set in motion and halted in any preferred way, either directly by manual operation, or through automatic connections. It is highly desirable, however, that in a machine of this type said mechanism be set in operation automatically when the line of matrices, after they have been assembled and inspected, has been shifted into the molding station, the mechanism being halted after a complete cycle of operations has been performed. This arrangement permits the operator to assemble and inspect the line of matrices while the molding and distributing mechanism is inactive, the latter being set in operation when the line is shifted into the assembler, and continuing the work of molding the slug and distributing the matrices while the next line is being set. I have provided an arrangement suitable for this purpose, and in the preferred form shown I employ a construction similar in many respects to that of the standard linotype, though obviously many variations therein may be made. This construction includes a standard expanding clutch 163 (Fig. 2) connecting the constantly rotating pulley 164 with shaft 160. Clutch 163 is normally forced into engagement with pulley 164 by a spring 165 (Fig. 2^a) within a hollow end portion 166 of shaft 160, said spring bearing against a clutch rod 167 slidable within the shaft end 166 and provided with transverse pins passing through slot 168 in said tubular end 166 and into engagement with a collar 169. With this arrangement, which is the usual construction on standard linotype machines, it will be apparent that the clutch is normally maintained by the spring 165 in active position, but may be shifted into inactive position by moving collar 168 outwardly toward pulley 164. For this purpose, I may employ a construction, shown best in Fig. 2^a, which includes a bell crank lever 170 pivoted on the frame of the machine, one arm of which terminates in a fork 171 engaging collar 169, the other arm of the bell crank being pivoted to a block 172 on which catch rod 173 is slidably mounted, a spring 174 bearing against block 172 and a collar or nut 175 on the upper end of said catch rod tending to maintain the rod in elevated position. The lower end of catch rod 173 is provided with means, such as shoulder 176, engaging a complementary member, such as lug 177, mounted on gear 162. With this arrangement, it will be apparent that when the cam shaft revolves in a clockwise direction, looking from the front of the machine, lug 177, contacting with shoulder 176, will operate to depress the arm 170 of the bell crank lever through the resilient pressure of spring 174, throwing shoulder 169 to the right and releasing the

clutch, at the same time affording a positive, yet resilient, stop, for gear 162 and the cam shaft 111 upon which said gear is mounted. The weight and friction of the parts will be sufficient to maintain said catch and bell crank in position with the clutch out of engagement, as in the standard linotype construction, though, if desired, any suitable means, such as a latch or ratchet, may be employed for preventing the accidental reengagement of the clutch. 70

When the cam shaft 111 is to be started, it is only necessary with the construction disclosed to shift catch rod 173 away from gear 162, breaking the connection between shoulder 176 and lug 177 and permitting spring 165 to force the clutch into operative position, spring 174 raising shoulder 176 to a point where it will not engage lug 177 when the cam shaft starts to rotate. 80

Any desired mechanism for shifting catch rod 173 outwardly to start the rotation of the cam shaft 111 may be employed. I prefer to provide means connected to the line-shifting mechanism operative only when the line has been shifted completely into position in the molding station, this arrangement preventing conflict between the parts, and assuring perfect timing of the various operations regardless of the time employed in setting the line. While the latch-releasing connection may be made with any part of said line-shifting mechanism, I prefer to release the latch from shift rod 52, one construction for this purpose including a link 178 (Fig. 3) connecting collar 57 with a rock lever 179 centrally pivoted on the frame of the machine and connected at its other end by link 180 (Figs. 2 and 2^a) with a block 181 mounted on catch rod 173, said block preferably being vertically adjustable on the rod, and serving to limit the vertical movement of said rod when the catch is released. With this arrangement, the movement of shift rod 52 to the left, during which the line is being shifted from the assembler to the molding station, will operate through link 178 to rock the lever 179 about its pivot, link 178 being so arranged that, at the limit of the movement of shift rod 52 to the left, said link will draw the end of rock lever 179 forward, forcing link 180 to the rear and releasing the latch rod 173. This specific connection between the shift rod 52 and the latch construction is, however, obviously capable of many variations; and my invention is not limited to the specific arrangement disclosed. 95

The general mode of operation of the machine is as follows. The assembler, molding station, and mold slot are set to accommodate a line of certain length, indicated on dial 88 by the pointer on handwheel disk 89. The return of the line-shifting mechanism has dropped a matrix slide block into the 100

assembler by engagement of the trip arm 70 with the block releasing key bar 68. The operator, by suitable manipulation of keys 26, releases from compartments 23, the matrices, which are conveyed in succession by belt 24 over guide plates 27 into the assembler, the matrices already in the assembler being forced forward by pressure of the points of the rotating star wheel 28. The spacers are dropped from magazine 34 at suitable points. When the line is nearly full, as shown by the proximity of the matrix slide block to the stop arm 37, the operator inspects the line through sight opening 33, making such changes and adjustments therein as are necessary. He then depresses key 40, which retracts stop arm 37 from the path of the matrices and at the same time lifts latch 63 out of its notch in shift rod 52, permitting said rod to be sharply thrust to the left by spring 56, and carrying with it the shift block 47. As the block 47 travels to the left, thumb 50 rises into position to engage the last matrix, and during further travel of the shift rod and block, forces the matrices along the guide channels in the assembler and into the registering channels in the elevator, the expandable matrix slide block 65 exerting sufficient pressure against the side walls of the assembler and elevator to prevent tilting and consequent jamming of the matrices. As soon as thumb 50 has forced the last matrix into position to the left of the path of the plate 148, which forms the right-hand wall of the molding station, latch rod 173 is tripped through its connection to the shift rod 52, permitting the clutch to engage the driving pulley 164 and starting the rotation of the cam shaft. Several operations are started when the cam shaft commences to rotate, the most rapid being the return of the shift rod to the right, where it is located in position by engagement of latch 63 with slot 64 in said rod, tripping key bar 68 to drop a matrix slide block into the assembler just before the bar is located in position. As soon as this return has taken place, the operator is free to set up the next line, while the molding and distributing mechanisms are at work, thus eliminating delay in operation.

As soon as cam shaft 111 starts, pot 131 is moved forward, plate 148, forming the end wall of the mold slot and molding station, passing through the mold and projecting into position at the rear of the matrices. As soon as said plate 148 is substantially in engagement with the rear matrix, justifying slide 122 is elevated, justifying the line, the timing preferably being such that this justification is completed substantially at the same time that the forward motion of the pot has advanced the mold into engagement with the matrices. At this moment, the

molten metal is forced through spout 134 into the mold slot, and the slug is formed against the intaglio portions of the matrices. After a momentary delay necessary for the slug to set, the pot recedes, the mold following it for a distance sufficient to clear the lower matrix shoulders, and the elevator at once rises, distributor block 154 being simultaneously retracted so that when the elevator has reached its uppermost position, the block may again be shifted to the right by spring 157, transferring the matrices from the elevator to the distributing channel 153, the elevator returning at once to normal position in register with the assembler. 80

During the motion of the elevator, and as soon as the pot spout 134 has been retracted from the rear wall of the mold, the ejector blade 101 is shifted to the right by the action of rock lever 190 on carriage 105, ejecting the slug from the right-hand end of the mold past the trimmers 116 and 117, which plane the top, bottom and rear face of the slug as it is ejected. After the slug has been ejected, the return of rock lever 109 permits carriage 105 to be shifted to the left by spring 113, until pin 103 contacts with the left-hand wall of recess 104, thus returning the ejector to set position. Any preferred form of discharge chute and gallery may be employed for receiving the ejected slug, the arrangement thereof being purely optional; and these parts have been omitted as they form no part of my invention. The parts are now in their original 100 position, and the rotation of cam shaft 111 is halted by the engagement of lug 177 with shoulder 176 on the latch rod 173, depressing the rod and shifting the clutch out of engagement with pulley 164, springs 174 and 105 165 serving to bring the cam shaft to a gradual stop. It will be noted that the return of shift rod 52 to its locked position will serve to hold block 181 at a fixed distance from gear 162, so that positive engagement of lug 177 and shoulder 176 is assured and the cam shaft is necessarily halted in proper position for starting the 110 cycle of operations.

When the operator desires to change the 115 length of line, it is only necessary for him to grasp hand wheel 84, retract it to clear disk 87 from disk 88, and rotate the hand wheel until the indicator thereon is opposite the proper figure on dial 88, when the 120 release of the hand wheel will lock the parts in proper position. The rotation of the hand wheel operates through pinion 82 and rack 83 to shift the end wall 78, to the right or left, into the proper location. As the 125 stop arm 37 of the assembler is rigidly connected to the end wall 78, this operation simultaneously adjusts the capacity of the assembler to the same length of line as the molding station. Furthermore, as the ejec- 130

5 tor blade 101 is connected through pin 103 to the end wall 78 and is normally maintained in registered position therewith by spring 113, which holds said pin against the left-hand wall of recess 104 in the end wall 78, the adjustment of said end wall will simultaneously locate the face 102 of ejector blade 101 properly in the mold slot, so that the length of the slug cast will be 10 the same as the length of the line of matrices for which the assembler and molding station are adjusted, the ejector blade being free to travel to the right to eject the slug, always returning to registered position 15 through engagement thereof with the end wall 78.

When it is necessary to change the height of the type, the upper mold plate 92 is taken off by releasing the handscrews 94, and the 20 liners 114 are replaced by others, trimmer knives 116, which are preferably carried by the liners, being automatically spaced apart the right distance. If desired, it will be apparent that the liners 114 may be so 25 proportioned and constructed that they may be slid forward out of the mold without removing the top plate, suitable connection between mold plate 101 and arm extension 90 being provided. However, with the form 30 disclosed, I prefer to replace the ejector blade 101, which of course with this arrangement must be changed every time the height of type is varied, by lifting the blade off of pins 120 while the mold is open, replacing 35 the lower liner 114, then the new ejector blade 101, and finally returning top mold plate 92 to active position, and turning down handscrews 94.

40 While I have described a specific form in which the mechanism for shifting the line of matrices from the assembler into the molding station returns to its inactive position before the next line is composed, it will be apparent that the general construction 45 herein disclosed may readily be modified to permit the composition of a new line prior to the complete return of said shifting mechanism to its position at the right-hand limit of its travel; and my invention 50 includes such a construction. Furthermore, while I have described a combination of parts which operate in succession to produce a complete result, important features of my invention involve these separate parts alone, 55 and may be embodied in connection with similar parts in machines which do not employ the broad combination of units which I disclose. My invention, therefore, includes the specific improvements in these separate 60 parts.

65 It will be readily apparent that I have provided a machine which is extremely simple because of the relatively small number of parts, the elimination of intricate and weak mechanism, and the direct handling

of the matrices and slug. Furthermore, the parts have been so devised and arranged that they may be readily and rapidly inspected, removed and replaced. I have also very substantially reduced the weight and 70 size of the machine. The arrangement is also such that extremely rapid operation may be had, and consequently a smaller number of matrices is necessary, owing to the greatly reduced path through which the matrices 75 travel, and consequently the increased speed with which they may be returned to their respective magazine compartments.

It will be evident that, with a machine such as I have disclosed, embodying not 80 merely specific improvements but very broad changes in construction and operation of certain parts of the machine, a great many alternative constructions for the majority of the operations may be employed 85 and could be devised by a mechanic skilled in the art. Some of these variations have been indicated, and others will be readily apparent. I wish it, therefore, to be understood that I do not consider my invention 90 as limited to the specific construction of the various parts; but it includes broadly the general arrangement and combination of operating elements disclosed which avoid the difficulties and possess the advantages 95 set forth in the first part of this specification.

I claim:

1. In a machine of the class described, means for assembling a plurality of matrices 100 to form a line of predetermined length, means including an adjustable mold for molding from said matrices a line of type of predetermined length, and unitary means for adjusting said assembling and molding 105 means to accommodate and produce a predetermined length of line.

2. In a machine of the class described, means for assembling a plurality of matrices to form a line of predetermined length, 110 means including an adjustable mold for molding from said matrices a line of type of predetermined length, and a member for adjusting said assembling and molding means to accommodate and produce a pre- 115 determined length of line.

3. In a machine of the class described, means for assembling a plurality of matrices to form a line of predetermined length, means including an adjustable mold for 120 molding from said matrices a line of type of predetermined length, and a manually rotatable member for adjusting said assembling and molding means to accommodate and produce a predetermined length of line. 125

4. In a machine of the class described, means for assembling a plurality of matrices to form a line of predetermined length, means including an adjustable mold for molding from said matrices a line of type of 130

- predetermined length, a member for adjusting said assembling and molding means to accommodate and produce a predetermined length of line, and means cooperating with 5 said member to indicate the length of line for which said assembling and molding means are set.
5. In a machine of the class described, an assembler, including a support and an adjustable end stop for a line of matrices, a molding station, including a support and an adjustable end stop for the line of matrices, a mold, including a mold slot, an adjustable end wall for said slot, and means 10 for simultaneously adjusting both of said stops and said wall to change the length of line.
6. In a machine of the class described, an assembler, including a support and an adjustable end stop for a line of matrices, a molding station, including a support and an adjustable end stop for the line of matrices, a mold, including a mold slot, an adjustable end wall for said slot, and means for adjusting 15 both of said stops and said end wall to change the length of line by a single manipulation.
7. In a machine of the class described, an assembler, including a support and an adjustable end stop for a line of matrices, a molding station, including a support and an adjustable end stop for the line of matrices, a mold, including a mold slot, an adjustable end wall for said slot, and a single 20 adjusting member adapted to adjust both of said stops and said wall to vary the length of line.
8. In a machine of the class described, an assembler, including a support and an adjustable end stop for a line of matrices, a molding station, including a support and an adjustable end stop for the line of matrices, a mold, including a mold slot, an adjustable end wall for said slot, unitary 25 means for adjusting both of said stops and said wall to vary the length of line, and means for indicating the length of line for which said assembler, molding station and mold slot are set.
- 50 9. In a machine of the class described, an assembler, including a support and an adjustable end stop for a line of matrices, a molding station, including a support and an adjustable end stop for the line of matrices, a mold, including a mold slot, an adjustable end wall for said slot, unitary means for adjusting both of said stops and said wall to vary the length of line, and a scale cooperating with said unitary means 55 to indicate at all times the length of line for which said assembler, molding station and mold slot are set.
- 60 10. In a machine of the class described, an assembler, including a support and an adjustable end stop for a line of matrices, a 65 molding station, including a support and an adjustable end stop for the line of matrices, a mold slot, an adjustable end wall for said slot, manually rotatable means for adjusting both of said stops and said wall to change the length of line, and a dial bearing a scale concentric with the axis of said rotatable means cooperating with a suitably designated portion of said rotatable means to indicate the length of line 70 for which said assembler, molding station and mold slot are set.
11. In a machine of the class described, an assembler, including a support and an adjustable end stop for the line of matrices, a molding station, including a support and an adjustable end stop for the line of matrices, a mold adjacent said molding station, including a mold slot and an adjustable end wall for said mold slot, means connecting 75 said end wall and the adjustable stop of the molding station to maintain said wall and stop in register during adjustment of said stop, and means for adjusting both of said stops to vary the length of line, the adjustment of said molding station stop operating to adjust the end wall of the mold slot.
12. In a machine of the class described, an assembler, including a support and an adjustable end stop for a line of matrices, a molding station, including a support and an adjustable end stop for the line of matrices, a mold, including a mold slot, an adjustable end wall for said slot, means connecting said 80 stops and end wall to produce homologous 85 movement during adjustment, and means for adjusting one of said three adjustable elements to change the length of line, the construction being such that the adjustment of said one element will be effective to adjust the remaining two elements.
13. In a machine of the class described, an assembler, including a support and an adjustable end stop for a line of matrices, a molding station, including a support and an adjustable end stop for the line of matrices, a mold, including a mold slot and an adjustable end wall for said slot, means connecting said molding station stop with said 90 end wall, means connecting said molding 95 station stop with said assembler stop, and means for adjusting one of said end stops to change the length of line, the construction being such that the adjustment of said end stop will be operative through said connecting means to adjust the other stop and said end wall to accommodate and produce a predetermined length of line.
14. In a machine of the class described, an assembler, including a support for a line of matrices and an end stop for said line, movable longitudinally of said support to vary the length of line, a molding station, including a support for a line of matrices and an end stop for said line, movable longitudinally of said support to vary the length of line, and a dial bearing a scale concentric with the axis of said rotatable means cooperating with a suitably designated portion of said rotatable means to indicate the length of line for which said assembler, molding station and mold slot are set.

- dinally of the support to vary the length of line, means for connecting said end stops to produce homologous longitudinal movement thereof, a mold, including a mold slot, an 5 adjustable end wall movable longitudinally of said slot, means for connecting said end wall with the molding station adjustable stop to produce homologous longitudinal movement of said wall and molding station 10 stop, and means for longitudinally shifting one of said three adjustable elements to change the length of line, the construction being such that the longitudinal shifting of any one of said three elements will shift the 15 remaining two elements and simultaneously adjust said assembler, molding station and mold, for a predetermined length of line.
15. In a machine of the class described, means for assembling a plurality of matrices to form a line of predetermined length, a molding station, means for shifting said line of matrices from the assembling means into the molding station, a mold horizontally aligned with said molding station, 20 means for bringing said mold and the line of matrices in said molding station into contact with each other, means for casting a slug in the mold against said line of matrices, and means for ejecting the slug endwise from the mold.
16. In a machine of the class described, an assembler, including a support and an adjustable end stop for the line of matrices, a molding station including a support and 25 an adjustable end stop for the line of matrices, unitary means for adjusting both of said stops to vary the length of line, and means for shifting the matrices from the assembler support directly to the molding station support.
17. In a machine of the class described, an assembler, including a support and an adjustable end stop for a line of matrices, a molding station, including a support and 30 an adjustable end stop for the line of matrices, a member connecting said end stops to maintain them in fixed relation, means for directly adjusting one of the stops to vary the length of line, the construction being such that the adjustment of one stop will effect corresponding adjustment of the other stop, and means for shifting the matrices from the assembler support directly to the molding station support.
18. In a machine of the class described, an assembler including matrix supporting walls, a molding station including matrix supporting walls, a stationary end stop for limiting the travel of the matrices in the 35 assembler, said assembler and molding station being located in alignment, means for shifting said end stop laterally from the matrix path, and means for shifting a line of matrices directly from the assembler into the molding station.

19. In a machine of the class described, an assembler, a molding station in alignment therewith, a normally stationary matrix stop in said assembler, means for adjusting said stop to vary the length of line, means 70 for retracting said stop laterally from the assembler, and means for shifting the line of matrices directly from the assembler to the molding station.

20. In a machine of the class described, 75 an assembler, a molding station in alignment therewith, a normally stationary matrix stop in said assembler, means for shifting the line of matrices from the assembler directly to the molding station, and means 80 for shifting said stop laterally out of the matrix path operatively connected to the line shifting means.

21. In a machine of the class described, 85 an assembler, a molding station in alignment therewith, a normally stationary matrix stop in said assembler, means for shifting the line of matrices from the assembler directly to the molding station, means for shifting said stop laterally out of the matrix path operatively connected to the line shifting means, and unitary means for concurrently actuating both the line shifting means and the stop withdrawing means.

22. In a machine of the class described, 90 an assembler, including means for slidably supporting a line of matrices, a molding station, including means for slidably supporting said line normally in alignment with and adapted to shift a line directly from the assembler supporting means, an end wall for limiting the length of line supported in the molding station, an end stop for limiting the length of line in said assembler, means connecting said end stop and wall to maintain them in fixed relation, means for shifting said line from the assembler into the molding station, means for moving the assembler end stop into inoperative position prior to said shift, and means 100 for adjusting one of said line limiting devices, which include said stop and wall, to vary the length of line, the construction being such that the adjustment of one device will simultaneously adjust the other device.

23. In a machine of the class described, 110 means for assembling a plurality of matrices to form a line of predetermined length, a molding station, means for shifting said line of matrices from the assembling means into the molding station, a mold adjacent said molding station, means for bringing said mold and the line of matrices in said molding station into contact with each other, means for casting a slug in the mold against said line of matrices, and means for ejecting the slug endwise from the mold, in a direction opposite to the advance of the matrices.

24. In a machine of the class described, 115 means for assembling a plurality of matrices

- to form a line of predetermined length, a molding station, means for shifting said line of matrices from the assembling means directly into the molding station, a mold adjacent said molding station, means for bringing said mold and the line of matrices in said molding station into contact with each other, means for casting a slug in the mold against said line of matrices, and means for ejecting the slug endwise from the mold.
25. In a machine of the class described, an assembler including a support for a line of matrices, a molding station including a support for said line, and means for shifting said line from the assembler support to the molding station support, including line-engaging means, resilient means for actuating said line-engaging means to shift the line, means for returning the line-engaging means to initial position, means directly engaging the line-shifting means to retain the latter in said initial position against the pressure of the resilient means, manually releasable means to permit said resilient means to become effective immediately upon such release for shifting the line.
26. In a machine of the class described, an assembler including a support for a line of matrices, and an end stop for limiting the length of line, a molding station including a support for the line of matrices in register with the assembler support, means for shifting said line from the assembler support to the molding station support, and unitary means for simultaneously moving the end stop to inoperative position and actuating said line-shifting means.
27. In a machine of the class described, an assembler, a normally stationary matrix stop in said assembler, means for adjusting said stop lengthwise of the assembler, and means for retracting said stop from the assembler, said latter means including a manually operated element and a fixed member actuated thereby adapted to maintain operative engagement with said stop regardless of the adjusted position of the stop.
28. In a machine of the class described, an assembler, a matrix stop therein, a mold station in alignment with the assembler, said station including an end wall or jaw adapted to engage one end of a matrix line, a member extending from said end wall to said stop and rigidly connecting the wall and stop, and means for simultaneously adjusting said wall and stop to vary the length of line.
29. In a machine of the class described, an assembler having a support for a line of matrices, line-receiving means, an end stop for limiting the length of line in said assembler, means for shifting said line from the assembler into said receiving means, and unitary manually operated means for shifting said end stop into inoperative position and thereafter actuating said line-shifting means.
30. In a machine of the class described, an assembler having a support for a line of matrices, line-receiving means, an end stop for limiting the length of line in said assembler, said end stop being adjustable longitudinally of the assembler to vary the length of line, means for shifting said line from the assembler into said receiving means, and unitary manually operated means for shifting said end stop into inoperative position and thereafter actuating said line-shifting means.
31. In a machine of the class described, an assembler including a support for a line of matrices, line-receiving means, means for shifting said line longitudinally from said support into the receiving means including a matrix-engaging member, a reciprocating element operatively connected thereto, resilient means engaging said reciprocating element normally tending to move said element and member to shift the line, a rotating shaft, means connected to said shaft for returning said element to inactive position, latch means for retaining said element and member in inactive position, an end stop for limiting the length of line in said assembler, and manually operated means concurrently operative to shift said stop into inoperative position and release the latch to permit said resilient means to shift the line.
32. In a machine of the class described, an assembler, including a support for a line of matrices, a rotating star wheel for forcing successive matrices into position on said support, and means for shifting the assembled line of matrices longitudinally from said support, said shifting means including a matrix engaging member normally located out of the path of said matrices during assembly, and means for shifting said member longitudinally and transversely of the matrix line into engagement with the last matrix in the line and continuing said longitudinal shift to force the line of matrices from the support through the action of said member.
33. In a machine of the class described, an assembler, including means for slidably supporting a line of matrices, and provided with a sight opening through which the advance end of the line may be observed, and a stationary end stop for said line extending through said opening into the path of the line.
34. In a machine of the class described, a mold having a molding slot, a support for maintaining a line of matrices in register with the slot, means for limiting the length of the matrix line carried by the support, and unitary means for adjusting simulta-

neously both the length of the slot and the limiting means to change the length of type line.

35. In a machine of the class described, a 5 mold maintained in substantially horizontal position and having a molding slot, an adjustable end wall for the slot, a support for maintaining a matrix line in register with the slot, means for limiting the length of 10 matrix line carried by the support, including a wall adjustable longitudinally of the support, and unitary means for adjusting both the slot end wall and the support wall to change the length of type line.

15 36. In a machine of the class described, a mold having a molding slot, an adjustable end wall for the slot, a support for maintaining a matrix line in register with the slot, means for limiting the length of matrix 20 line carried by the support, including a wall adjustable longitudinally of the support, means directly connecting the end wall of the slot and the support wall adapted to maintain them in registered relation, and 25 means for adjusting the support wall to change the length of line, the construction being such that the adjustment of the support wall will simultaneously adjust the end wall of the slot.

30 37. In a machine of the class described, a mold having a molding slot, a longitudinally adjustable end wall therefor, a support for maintaining a line of matrices in register with the slot, means for limiting the length 35 of matrix line on the support, said means including a wall adjustable longitudinally of the support, means connecting the adjustable slot wall and the adjustable support wall adapted to maintain said walls in 40 register, a rack connected to the support wall, a pinion meshing with the rack, and means operable from the front of the machine for rotating the pinion to adjust the position of the support wall and slot wall 45 so as to change the length of type line.

38. In a machine of the class described, a mold having a molding slot, an ejector forming one end of the slot and longitudinally slid able therein, a support for maintaining a line of matrices in register with the slot, means for limiting the length of the 50 line of matrices, including an end wall adjustable longitudinally of the support, means for reciprocating the ejector longitudinally in the slot to eject a slug therefrom, means for maintaining the ejector and the adjustable support wall in registered relation, and manually operable means for adjusting the support wall to vary the 55 length of type line.

39. A machine for casting type in the form of an integral line, comprising a mold having a molding slot, an ejector forming an end wall of the slot and longitudinally slid- 60 able therein, a support for maintaining a

line of matrices in register with the slot, means for limiting the length of the matrix line including an end wall adjustable longitudinally of the support, means for advancing the ejector to eject a slug from the slot, 70 resilient means for retracting the ejector, means for maintaining the ejector and support wall in registered relation, including interengaging elements normally maintained in engagement by said resilient means, and manually operable means for adjusting the position of the support wall to change the length of type line.

40. In a machine of the class described, a mold having a molding slot, an ejector forming an end wall of the slot and longitudinally slid able therein, a support for maintaining a line of matrices in register with the slot, means for limiting the length of the matrix line including an end wall adjustable longitudinally of the support, means for shifting said mold and support wall toward and away from each other, means for advancing the ejector to eject a slug from the slot, resilient means for retracting the ejector, means for maintaining the ejector and support wall in registered relation, including interengaging elements normally maintained in engagement by said resilient 85 means, and means for adjusting the position of the support wall to change the length of type line.

41. In a machine of the class described, a mold having a molding slot, a support for maintaining a line of matrices in register with the slot, and a unitary end wall movable in unison with the metal pot relative to the matrix support, adapted to close one end of the slot and directly to engage said matrices and form an abutment for one 100 end of the line thereof.

42. In a machine of the class described, a mold having a molding slot, a support for maintaining a line of matrices in register with the slot, a unitary end wall operably supported by the metal pot and closing one 105 end of the slot and directly engaging said matrices and forming an abutment for one end of the line thereof, and means for shifting said wall into and out of operative relation to said slot and support.

43. In a machine of the class described, a mold having a molding slot, a longitudinal support for maintaining a matrix line in register with the slot, means for shifting said line onto the support from one end thereof, a unitary end wall operably supported by the metal pot for closing one end of the slot and directly engaging said matrices and forming an abutment for one end 110 of the line thereof, and means for locating the wall in register with the slot and across the path of the matrices after the line has been shifted onto the support.

44. In a machine of the class described, a

5 mold having a molding slot, a support for maintaining a line of matrices in register with the slot, an oscillating pot having a spout shifted into and out of engagement with the slot, an end wall adapted to close one end of the slot and to limit the motion of the matrix line on the support in one direction, and a connection between said wall and pot adapted to shift the wall into operative relation to the slot and support upon the advance of the pot to pouring position, and to retract the wall from operative position upon the retreat of the pot.

10 45. In a machine of the class described, a mold having a molding slot, a support for maintaining a line of matrices in register with the slot, an oscillating pot having a spout shifted into and out of engagement with the slot, an end wall mounted on the pot and adapted to close one end of the slot and to limit the motion of the matrix line on the support in one direction, the construction being such that the advance of the pot to pouring position will shift the end wall

15 20 25 into operative relation to the slot and support, and the retreat of the pot will withdraw the end wall from said operative position.

30 46. In a machine of the class described, a mold having a molding slot, supporting means for said mold permitting mold movements in a horizontal plane only, a support for maintaining a line of matrices in register with the slot, and means for moving said mold horizontally upon said supporting means into and out of engagement with the line.

40 47. In a machine of the class described, a molding station matrix support, a mold support, a mold slideable thereon toward and from said matrix support, an oscillating pot adapted to shift said mold into operative relation to said matrix support, and means for ejecting a slug lengthwise from the mold.

45 48. In a machine of the class described, a fixed base adapted to maintain a mold in horizontal position, a mold horizontally slideable thereon and having a molding slot, a support for maintaining a line of matrices in register with the slot, an oscillating pot adapted during its forward movement to engage the mold adjacent said slot and shift the slot into engagement with the line of matrices, and spring means for retracting the mold and slot from the line of matrices upon the retreat of the pot.

50 55 60 65 49. In a machine of the class described, a fixed base, a mold horizontally slideable thereon and having a molding slot, a support for maintaining a line of matrices in register with the slot, an oscillating pot adapted during its forward movement to engage the mold adjacent said slot and shift the slot into engagement with the line of matrices, spring means for retracting the

mold and slot from the line of matrices upon the retreat of the pot, and means for ejecting a slug endwise from the slot.

50 55 60 65 70 75 80 85 90 95 100 105 110 115 120 125 130 A machine for casting type in the form of an integral line, comprising a mold including a body portion provided with a molding slot, the upper and lower faces of the slot being provided with longitudinal central elevations adapted to produce a slug having front and rear walls of full height, with a connecting web of reduced height, a movable wall for closing one end of the slot, an ejector having an end portion snugly fitting said upper and lower faces of the slot and longitudinally slideable therebetween.

51. A machine for casting type in the form of an integral line, comprising a mold, including an upper portion, a lower portion, a liner mounted below the upper portion, a liner mounted above the lower portion, a molding slot being located between said liners, and means for detachably mounting said liners upon the upper and lower portions respectively.

52. In a machine of the class described, a mold, including an upper portion, a lower portion, a liner mounted below the upper portion, a liner mounted above the lower portion, a molding slot being located between said liners, means for detachably mounting said liners upon the upper and lower portions respectively, and a slug trimmer mounted upon each of said liners.

53. In a machine of the class described, a mold, including an upper portion, a lower portion, a liner mounted below the upper portion, a liner mounted above the lower portion, a molding slot being located between said liners, means for detachably mounting said liners upon the upper and lower portions respectively, and an end wall for said slot mounted between and longitudinally slideable along said liners.

54. In a machine of the class described, a mold, including a body portion having a lower section and an upper section removable therefrom, a molding slot being located between said sections, a carriage slidably mounted on the body portion, an ejector blade detachably connected to the carriage, snugly fitting and longitudinally slideable in the slot, and liners detachably mounted in the upper and lower sections respectively to form upper and lower faces of the slot, the construction being such that the height of a slug may be changed by removing the upper section, detaching the liners and ejector, replacing them with suitable liners and ejector, and then returning the upper section to its position.

55. In a machine of the class described, means for assembling a plurality of matrices to form a line of predetermined length, means for molding from said matrices a line of type of predetermined length, means

for shifting said matrices in a direct lateral line from said assembling means to said molding means, and unitary means for adjusting said assembling and molding means to accommodate and produce a predetermined length of line.

56. In a machine of the class described, a mold having a molding slot, a support for maintaining a line of matrices in register

with the slot, a pot movable with respect to said mold, said pot having a projection adapted to enter one end of the mold slot and close the same and also to form an abutment for one end of said line of matrices.

Signed at St. Paul, Minnesota, in the county of Ramsey and State of Minnesota, this 16th day of February, A. D. 1920.

FRED C. DAMM.
